UNITED STATES PATENT OFFICE.

MINFORD S. CLARK, OF BROOKLYN, NEW YORK.

VENTILATING ATTACHMENT FOR WATER-CLOSETS.

SPECIFICATION forming part of Letters Patent No. 307,526, dated November 4, 1884.

Application filed April 11, 1884. (No model.)

To all whom it may concern:

Be it known that I, MINFORD S. CLARK, of Brooklyn, Kings county, and State of New York, have invented certain new and useful 5 Improvements in Ventilating Attachments for Water-Closets, of which the following is a specification.

This invention has reference to an improved attachment for water-closets by which 10 the ventilating-pipe may be conveniently attached to the hopper of the closet; and the invention consists of a water-closet the hopper of which is provided at the rear part with an enlargement or bulge, the top of the hopper 15 having an opening above the bulge, with a depressed seat and a detachable plate retained by a collar and fastening-screws, which collar also serves to attach the ventilating-pipe after the plate is removed.

20 In the accompanying drawings, Figure 1 represents a side elevation of a water-closet with my improved ventilating attachment. Fig. 2 is a plan of said ventilating attachment drawn on a larger scale. Figs. 3 and 4 are 25 vertical transverse sections of the same on line $x x$, Fig. 2, showing, respectively, the ventilating-opening of the hopper closed by a detachable plate and opened and connected to the ventilating-pipe.

30 Similar letters of reference indicate corresponding parts.

A in the drawings represents the hopper of my improved water-closet, which is made of cast-iron or other suitable material. At the 35 upper rear end of the hopper A is arranged an outwardly-bulging portion, a , which is made integral with the hopper A. The top B of the closet is provided with an opening, b , and having a circumferential seat, b' , said 40 opening being closed by a disk-shaped plate or cover, d , which is set into the seat flush with top B of the closet, and retained by a collar, e , having recessed ears e' at diametrically-opposite points, said cover being tightly 45 secured to the top B by screw-ports e^2 , that are screwed tightly up through the top B from the under side of the same, so as to prevent gases from passing up along the threaded shanks. The bolts are provided above the 50 top B with nuts and washers e^3 , that are applied to the upper ends of the threaded shanks of the bolts at the top of the collar e . The

covering-plate d is permanently retained in position by the bolted collar e , the ventilating-opening being kept closed while the closet 55 is shipped and in case it is not desired to ventilate the hopper of the closet. Whenever it is desired to attach a ventilating-pipe to the hopper, the plate d is removed and the outwardly-bent flange of the ventilating-pipe f 60 secured to the seat b' by the collar e , as shown in Fig. 4, the collar being then secured in position by the bolts e^2 . By this arrangement it is not necessary to cut a hole in the top B or hopper A, for soldering on the ventilating- 65 pipe, as heretofore, whereby labor is saved to the plumber and a more convenient mode of attachment of the ventilating-pipe provided.

Having thus described my invention, I claim as new and desire to secure by Letters Patent— 70

1. The combination of a water-closet hopper, A, having an enlargement or bulge, a ; at the upper rear end, top B, having an opening, b , a detachable plate, d , a collar, e , and screw-bolts e^2 , for fastening the plate d to the 75 top B, substantially as set forth.

2. In a water-closet, the combination of the hopper A, having a bulge, a , a top, B, having an opening, b , and seat b' , a detachable covering-plate, d , a collar, e , having recessed ears e' , and fastening nuts and bolts $e^2 e^3$, substantially as set forth.

3. The combination of the hopper A, having a bulge, a , made integral therewith, a top, B, having an opening, b , a detachable covering-plate, d , a collar, e , and bolts e^2 , screwed from the under side through the top, and nuts e^3 , applied to the upper ends of the bolts, substantially as set forth. 85

4. The combination of a water-closet hopper A, having an enlargement or bulge, a , at the upper rear end, a top, B, having an opening, b , above the bulge a , a collar, e , and screw-bolts $e^2 e^3$, for fastening the collar to the top, so as to secure either a detachable covering- 95 plate, d , or the ventilating-pipe f , substantially as set forth.

In testimony that I claim the foregoing as my invention I have signed my name in presence of two subscribing witnesses.

MINFORD S. CLARK.
